UNITED STATES PATENT OFFICE

ARTHUR P. HOLDEN AND PHILIP MORGAN, OF TORONTO, ONTARIO, CANADA, ASSIGNORS, BY MESNE ASSIGNMENTS, TO FESS OIL BURNERS OF CANADA LIMITED, OF TORONTO, ONTARIO, CANADA

OVERFLOW RECEPTACLE FOR OIL BURNERS

Original application filed June 29, 1925, Serial No. 40,340. Divided and this application filed October 3, 1929. Serial No. 397,048, and in Canada June 29, 1925.

The principal objects of the invention are to minimize the danger of flooding in oil burning furnaces in the event of the failure of the ignition, and to provide a very compact arrangement for the purpose which will receive any oil escaping unburned from the nozzle and from which said oil may be very easily discharged prior to re-starting the burner into operation.

- 10 The principal features of the invention consist in the novel construction of a receptacle casing which is pivotally mounted on the end of the overflow pipe leading from the combustion chamber to receive the discharge therefrom, the casing being adapted to be swung on its pivotal mounting to drain the oil therefrom and being adapted to house a suitable switch mechanism actuated by a float in the casing.
- 20 A further feature consists in providing a stop on the casing adapted to engage the overflow pipe to limit the swinging movement of the casing thereon.

In the drawings, Figure 1 is a perspective view of the casing showing its arrangement on the overflow pipe in its overflow receiving position.

Figure 2 is a perspective view of the device illustrated in Figure 1 showing the manner in which the receptacle may be swung to effect the removal of the oil therefrom.

Figure 3 is a part section, part elevational view of the device illustrated in Figures 1 and 2.

35 In the type of power driven oil burners now so extensively used for domestic heating purposes it is particularly desirable that some means be provided for taking care of the discharged oil in the event of the failure of the oil to ignite, due often to an interruption in the ignition.

It has been found that under such conditions and with present equipment in the event of failure of the flame at the burner for some reason other than the actual shutting off of the power, the oil will still continue to be delivered to the burner by the pump and this oil failing to ignite flows down into the furnace and rapidly floods the same.

50 In our co-pending United States applica-

tion, Serial No. 40,340 filed June 29, 1925, we have described an automatic form of cut out which is actuated by this excess amount of oil in the furnace to effect the shutting off of the main motor circuit in the event of the furnace becoming flooded, so that the motor will discontinue pumping further oil to the burner. The present application is a division of application Ser. No. 40,340, such application being now Patent 1,736,198 granted Nov. 19, 1929.

The present invention is directed to a particularly effective means for taking care of the excess or overflow oil from the furnace from which the oil may be very conveniently and quickly emptied, so that it may be readily re-set before the burner is again set into operation, it being important that such apparatus cannot be left in an inoperable condition.

In the construction herein shown the overflow pipe 1 which leads from the furnace is connected to a suitable pan or other receiver that will readily catch the liquid oil discharged from the burner nozzle when it is not being ignited.

The pipe 1 leads outside of the furnace and extends into a casing 2 which is pivotally mounted upon the pin 3 which extends through the pipe close to its outer end and through the lugs 4 in the side of the casing.

The said casing is formed with a substantially cylindrical well portion 5 which is adapted to house the switch actuating float 6 as fully described in our co-pending application above referred to.

The side portions 7 of the lugs 4 extend forwardly in the form of a lip which fits snugly around the underside of the pipe 1 and connects with sloping spout-shaped portion 8 which preferably extends well down to the lower extremity of the cylindrical float well portion 5 for a purpose to be hereinafter referred to.

A cover 9 closes the top of the well 5 and is provided with an upwardly flaring lip 10 at the forward side which registers with the side walls of the lugs 4 and allows the casing to be swung or tipped upwardly to the position shown in Figure 2 where the lip 100

engages the top of the pipe 1 and arrests the casing against further movement.

A suitable casing 11 is mounted on the cover 9 which forms a convenient housing for 5 a suitable switch mechanism to which the float is adapted to be connected.

In the event of the liquid oil escaping from the burner and flowing through the pipe 1, it flows into the well 5 where it is adapted to 10 raise the float 6 therein as described in our co-pending application for the purpose of operating the electric switch to stop the operation of the burner mechanism.

Before starting the burner into operation 15 again, it is necessary to drain the oil from the float well 5 and this is accomplished in a very simple manner by merely tilting the casing 2 upon its pivot to the position shown in Figure 2 which allows the oil to flow therefrom out of the spout 8, which as previously 20 stated extends well down to the lower extremity of the float well portion 5 so that the oil will be completely drained therefrom.

The lip 10 effectively prevents the casing 25 from being tipped past the centre of gravity so that when it is released, it will swing back of its own weight to its normal position on the pipe 1 and remain in this position in readiness should a further overflow of oil 30 occur.

In this way the casing cannot be accidentally left in a position where it will not receive the overflow, and when used in conjunction with the float actuated switch mechanism 35 described in our co-pending application will provide a very compact and desirable combination which will ensure definite protection from the dangers attending the flooding of oil burning furnaces.

40 What we claim as our invention is:

1. An overflow receptacle for oil burners, comprising the combination with an overflow pipe, of a casing pivotally secured at the end of said overflow pipe and having a float 45 well formed therein adapted to receive a float, said casing being formed with a spout extending angularly upward from the lower extremity of the float well and embracing said pipe at the upper end, said spout being 50 adapted when the casing is tilted upwardly on its pivot to drain the oil from said float well, and a cover secured to said casing having a lip sloping upwardly above said overflow pipe and adapted to engage the latter 55 to limit the upward tilting movement of the casing.

2. An overflow receptacle for oil burners, comprising the combination with an overflow pipe, of a casing pivotally suspended 60 from said pipe and adapted to receive the discharge therefrom, said casing being adapted to be tilted on said pivot and having a drain channel sloping angularly outward from the bottom of the casing whereby 65 the complete draining of the oil therefrom

will be effected with the minimum pivotal movement of said casing.

3. An overflow receptacle for oil burners, comprising the combination with an overflow pipe, of a casing pivotally suspended 70 from said pipe and adapted to receive the discharge therefrom, and a spout in said casing receiving the outer end of said overflow pipe, said spout being sloped angularly outward from the bottom of the casing whereby upon the tilting of said casing on its pivot a limited degree the oil will be completely drained 75 from said casing.

4. An overflow receptacle for oil burners, comprising the combination with an overflow pipe, of a casing having a pouring spout sloping outwardly and upwardly from the normally lowermost portion thereof and receiving the discharge end of said pipe, said spout having side lugs arranged at opposite 80 sides of the pipe, a pin spaced from the outer extremity of said spout and extending through said pipe and lugs and pivotally securing the casing to the pipe, the outer portion of said spout engaging said pipe to normally support the casing in an upright position, said spout being adapted on the tilting of said casing on its pivot a limited degree to direct the oil completely therefrom through said spout.

5. An overflow receptacle for oil burners, comprising the combination with an overflow pipe, of a casing pivotally suspended below and receiving the discharge from said overflow pipe, said casing having a float well 90 therein extended laterally to one side forming a pouring spout sloping outwardly and upwardly from the bottom of the float well and adapted on the limited upward swinging 100 of the casing on its pivot to drain the oil completely from said well, and means for limiting the upward swinging movement of said casing.

6. An overflow receptacle for oil burners, comprising the combination with an overflow pipe, of a casing pivotally secured at the end of said overflow pipe and having a float well formed therein adapted to receive a float, said casing being formed with a spout extending angularly upward from the lower extremity of the float well and presenting an elongated open top, the sides of the open top of the spout being rounded to snugly embrace said pipe at the sides and form a substantial seal therewith closing the open top of said spout, said spout being adapted when the casing is tilted upwardly a limited degree on its pivot to drain the oil completely from said float well.

ARTHUR P. HOLDEN.
PHILIP MORGAN.
